CLAIM

The ornamental design for a paper dispenser, as shown and described.

DESCRIPTION

FIG. 1 is a front, side perspective view of a paper dispenser showing my new design;

FIG. 2 is a front, side perspective view thereof, with the casing portion being shown in an open position;

FIG. 3 is a rear perspective view of the casing portion of the paper dispenser shown in FIG. 1, with the wall mounting portion being removed for clarity;

FIG. 4 is a front, side perspective view of the wall mounting portion of the paper dispenser shown in FIG. 1, with the casing portion being removed for clarity;

FIG. 5 is a top perspective view thereof;

FIG. 6 is a rear perspective view thereof; and,

FIG. 7 is a bottom perspective view thereof.
